UNITED STATES PATENT OFFICE.

FREDERICK L. KEPPLER, OF NEW YORK, N. Y.

GLASS PAVEMENT-LIGHT.

1,385,688.

Specification of Letters Patent. Patented July 26, 1921.

Application filed February 5, 1917. Serial No. 146,641.

To all whom it may concern:

Be it known that I, FREDERICK L. KEPPLER, a citizen of the United States, residing at New York, in the county of New York and 5 State of New York, have invented a certain new and useful Improvement in Glass Pavement-Lights, of which the following is a specification.

My invention relates to improvements in 10 pavement lights and has for one object to provide a new and improved form of glass tile or pavement light which may be used in connection with the ordinary and well-known glass and concrete pavement construction. Another object is to provide such a tile as will have increased strength and durability and will be less subject to abrasion. Another object is to provide a tile which will be non-slipping, which will not wear 15 smooth and which will preserve a rough and corrugated surface and which will prevent slipping no matter how far worn is the surface of the tile. My invention also relates to the process of producing such a tile.

20 The invention is illustrated more or less diagrammatically in the accompanying drawings, wherein—

Figure 1 is a section through one of my tiles;

25 Fig. 2 is a plan view of the tile;

Fig. 3 is a section through a modified form; and

Fig. 4 is a plan view of a still further modification.

30 Like parts are indicated by like characters in all the figures.

A is the ordinary type of rectangular flat pavement tile. It is surrounded by a downwardly extending skirt or flange A¹ corrugated on its outer side as at A², so that it 35 may be built into the structure of the pavement or wall as the case may be. A³, A⁴ are a series of pockets or holes cast into the upper surface of the tile. These pockets are cast rather than drilled or cut because of the 40 obvious difficulties in connection with drilling and cutting glass, but for the more important reason that by providing these holes the skin is increased in area thereby increasing the strength of the tile since in glass 45 castings the skin is the strongest part. A⁴, A⁵ are plugs made up of plastic material, preferably a concrete or cement, with a relatively large quantity of carborundum or 50 some other hard or resistant material. These pockets are filled with plugs of such

material which adhere rigidly to the sides of the glass and are level with the surface of the tile. These pockets may be as numerous as desired and in the preferred form 60 do not extend clear through the face of the tile and do not change the appearance of the under side of the tile in any way. They are scattered about and widely separated so as to interfere to the least possible degree 65 with the passage of light through the pavement tile and to weaken such tile to the least possible degree.

In the modified form shown in Fig. 3, the 70 perforations are deeper and the tile is curved or bossed downwardly as at B to provide a sufficient thickness of glass between the bottom of the tile and the pocket. In Fig. 4 is shown a further modified form wherein a single plug C is located in the center of a 75 circular tile C¹. The pockets may be of any desired depth, the shallower the better, provided they are deep enough to hold the necessary material.

It is understood, of course, that these different structures all operate on the same principle for the same purpose but under different structural conditions it is desired to have different tiles, and in fact many other different pavement lights are used and 80 my process and invention can be applied to any one of these.

The lower surface of the pavement tile is as shown formed on the areas set at different angles for the purpose of diffusing light and 85 minimizing the degree to which the opaque material in the pockets is visible from below.

It is understood that the process is carried out by casting the glass light and then pouring in a plastic material containing the carborundum or other hard material and then allowing it to set when the tile is finished. Of course, the material which is used must be such as will not on setting shrink away 90 from the wall of the tile or expand to crack 100 the tile, but many cements, well-known in the art are available.

The pavement light has the pockets widely scattered so as to present the fewest possible points of interference with the passage of 105 light rays therethrough and so as to weaken the pavement light or tile to the least possible degree. The surface of the inside of the tile is undulatory, varied, or provided with faces inclined to each other, and this 110 is true where the tile is provided with strengthening protuberances under the pock-

ets. The effect of these faces is to diffuse and scatter the light in such manner as to obscure or minimize the opaque appearance of the material in the pockets. The 5 under surface of the tile is so arranged, as constructed in the preferred form in Fig. 1, and the alternative form of Fig. 3, that the light rays falling on the upper surface pass out through the under surface practically 10 uninterrupted by the plugs, the angles of the under surface being such that the light rays are reflected across the under surface of the tile and the depressions filled with the opaque material practically do not interrupt the light passage and these lights when 15 in use present to the eye practically the same appearance as that of the ordinary tile.

It will be evident that while I have shown 20 in my drawings an operative device, still many changes might be made both in size, shape and arrangement without departing materially from the spirit of my invention, and I wish therefore, that my drawings be regarded as in a sense diagrammatic.

25 I claim:—

1. As a new article of manufacture, a tile unit comprising a glass body with a substan-

tially flat upper surface, a depending rim about its edge, a plurality of projections from the lower surface of the tile, within 30 the rim, shaped to form strengthening and light diffusing areas, and a series of abrasive plugs set in the upper surface of the tile above the projections, each plug lying well within the boundary of the projections 35 over which it is placed.

2. As a new article of manufacture, a tile unit comprising a glass body with a substantially flat upper surface and a plurality of projections from the lower surface of the 40 tile shaped to form strengthening and light diffusing areas, and a series of abrasive plugs set in the upper surface of the tile above the projection, each plug lying well within the boundary of the projection over which it 45 is placed.

In testimony whereof, I affix my signature in the presence of two witnesses this twenty ninth day of January, 1917.

FREDERICK L. KEPPLER.
